UNITED STATES PATENT OFFICE.

MATT A. KOMPULA, OF CALUMET, MICHIGAN.

IMPLEMENT FOR TWISTING WIRE.

1,252,590.

Specification of Letters Patent.

Patented Jan. 8, 1918.

Application filed March 8, 1917. Serial No. 153,370.

To all whom it may concern:

Be it known that I, MATT A. KOMPULA, a citizen of the United States, residing at Calumet, in the county of Houghton and 5 State of Michigan, have invented certain new and useful Improvements in Implements for Twisting Wire, of which the following is a specification.

My invention relates to improvements in 10 implements adapted for wrapping a section of wire around the end portion of a section of flexible hose or the like, having a rigid pipe projecting therein, for securely binding the hose to the pipe, and twisting 15 the ends of the wire, in a highly expeditious and convenient manner.

An important object of the invention is 20 to provide a device of the above mentioned character, which is of simple construction, inexpensive to manufacture, strong and durable.

Other objects and advantages of the invention will be apparent during the course of the following description.

25 In mines, it is customary to drive reciprocatory hammers and the like by compressed air, such compressed air being ordinarily fed through an iron pipe, terminating within the mine, near the hammer. A 30 flexible hose is connected with the hammer and secured to the pipe by having the pipe projecting into its opposite end. This end of the hose is clamped to the pipe by a binding wire, extending therearound and having 35 its ends twisted together.

I have found that considerable time is often lost in binding or clamping the hose to the iron pipe, and my invention provides means for doing this work in a highly expeditious and convenient manner.

40 In the accompanying drawings forming a part of this specification and in which like numerals are employed to designate like parts throughout the same,

45 Figure 1 is an edge elevation of a device embodying the invention,

Fig. 2 is a similar view of the opposite edge thereof,

50 Fig. 3 is a side elevation of the device, Fig. 4 is a similar view of the opposite side thereof,

Fig. 5 is an end elevation of the same,

55 Figs. 6 and 7 are side elevations of the device, illustrating the different steps in the use of the same, when twisting the wire, and,

Fig. 8 is a side elevation of the work having the wire twisted thereabout.

In the drawings, wherein for the purpose of illustration is shown a preferred embodiment of my invention, the numerals 10 and 11 designate the coacting handles of the tongs, carrying heads or disks 12 and 13. These disks are pivotally connected at their centers by means of a bolt or rivet 14.

60 The disk 12 is provided upon the forward side of its periphery with a groove or depression 15, starting at a point near its forward end and extending rearwardly and increasing in depth, with a laterally extending flange 16, guarding the other side thereof. The free end of the groove 15 discharges 65 into a lateral opening 17, passing through the outer face of the disk and this opening has a cutting edge 18. The disk 12 is provided with a binding post or pin 19, rigidly secured to its outer face, at a point arranged near and spaced from the opening 17. The disk 12 is provided upon its opposite side 70 with an opening 20, having a cutting edge 21, for a purpose to be described.

75 The coacting disk 13 is provided upon its periphery with a groove 22, starting from a point arranged near the forward end thereof, and extending rearwardly and increasing in depth, with a laterally extending flange 24, guarding the outer side thereof. The groove 22 leads into a lateral opening 25, passing through the outer face of the disk. The opening 25 has a cutting edge 26. The disk 13 is provided upon its opposite side with an opening 27 having a cutting edge 28, for a purpose to be described. The disk 13 is provided with a pair of binding posts or pins 25', as shown.

90 In the operation of the device, the wire 29 is passed about the work 30 and one end thereof arranged within the groove 15, carried through the opening 17, and wrapped about or secured to the binding post 19. The 95 other end portion of the wire is arranged within the groove 22, carried through the opening 26, wrapped about or secured to the binding posts 25'. As shown in Fig. 6, the coacting handles 10 and 11 are suitably opened, thus placing the desired tension upon the wire, prior to the turning movement of the device, whereby the wire 100 is twisted, as indicated in Fig. 7. After this twisting operation, the wire is loosened 105 from the binding posts and the coacting handles are further moved to an open posi-

tion so that the opening 17 is moved into registration with the opening 27 and the opening 25 into registration with the opening 21. The ends of the wire are then passed within these registering openings and the coacting handles moved to the closed position, the cutting edges of the opening serving as shears to cut the wire.

It is to be understood that the form of my invention herewith shown and described is to be taken as a preferred example of the same, and that various changes in the shape, size, and arrangement of parts may be resorted to without departing from the spirit of the invention or the scope of the subjoined claim.

Having thus described my invention, I claim:

A device of the character described, com-

prising a pair of pivoted coacting disks provided upon the forward portions of their peripheries with grooves having their rear ends in communication with lateral openings passing through the inner and outer sides of the disks, each disk being provided upon its edge opposite its first named opening with a second opening to coact with the first named opening of the other disk in cutting wire, a device carried by the outer side of each disk to secure the wire thereto, and handles carried by the disks for turning them upon their pivots.

In testimony whereof I affix my signature in presence of two witnesses.

MATT A. KOMPULA.

Witnesses:

W. J. GALBRAITH,
MATT OLLILA.
